UNITED STATES PATENT OFFICE.

ARTHUR A. MERRITT, OF COHOES, NEW YORK, ASSIGNOR, BY MESNE ASSIGNMENTS, TO W. PIERREPONT WHITE, HUGH WHITE, AND CLARENCE B. CROUSE, OF UTICA, NEW YORK.

MACHINE FOR SEWING ON FLAT BUTTONS.

SPECIFICATION forming part of Letters Patent No. 655,658, dated August 7, 1900.

Application filed May 3, 1897. Serial No. 634,875. (No model.)

To all whom it may concern:

Be it known that I, ARTHUR A. MERRITT, a citizen of the United States, residing at Cohoes, in the county of Albany and State of New York, have invented a new and useful Improvement in Button-Sewing Machines, of which the following is a full, clear, and exact description, reference being had to the accompanying drawings, forming a part of this specification, in explaining its nature.

The invention relates to the class of button-sewing machines known as "flat-bed" button-sewing machines; and it comprises means for providing the button-holder with a movement crosswise the line of feed or movement of the fabric to which the buttons are sewed and also a movement in the direction of the length of said line of feed or movement and for combining said movements, whereby buttons having two or four eyes may be attached by a single needle reciprocating upon a stationary vertical plane and its coöperating stitch-forming mechanism; and it further consists in means for varying the extent or degree of the said movements of the button-holder, which means are so organized and arranged as to be readily accessible from the top of the work-plate of the machine and require but a movement in one direction or the other to effect the adjustment desired.

In the drawings, Figure 1 is a view in left side elevation of a machine having the features of my invention. Fig. 2 is a view in horizontal section upon the dotted line 2 2 of Fig. 1 and in plan of the parts below said dotted line. Fig. 3 is a view of the work-plate in plan, showing the location of the button-holder-adjusting devices and also showing by dotted lines the relation between the said adjusting devices and the button-holder and its operating mechanism. Fig. 4 is a view of the machine inverted. Fig. 5 is a view in perspective of the devices for communicating longitudinal movement lengthwise the bed of the machine to the button-holder and its supporting slide or plate and also representing the means by which the degree or extent of this movement is adjusted. Fig. 6 is a view in

perspective of the devices for giving a lateral movement to the button-holder and its supporting slide or plate crosswise the bed of the machine and for adjusting the extent of said movement.

The needle A, shuttle-carrier, shuttle and shuttle-operating devices, and the button-holder B are like the corresponding parts referred to in my application Serial No. 620,844. The part C upon which the button-holder is mounted and by which it is moved is in some instances a slide having a longitudinal movement at intervals imparted to it by its operating-cam, and in some instances a lever, and in some instances a combined slide and lever. It is moved longitudinally by the cam-groove D in the under side of the cam-disk D', the said cam-groove being connected with said part C by means of the lever d, pivoted at d', the link d², the lever d³, pivoted at d⁴ to a sliding block d⁵ by a pivotal connection d⁶, which is adapted to be moved lengthwise the said lever d'. The pivotal connection is mounted in the slide-block d⁵, and the slide-block is movable to vary the position of the pivotal connection from a point close to the end of the slide or part C, where there will be no movement imparted to the slide C, to a position near the other end or outer end of the lever, at which point the greatest amount of movement will be given the slide or part D. The slide-block has an upward extension d⁷ at one side, which enters the long narrow hole or slot d⁸ in the bed-plate, (see Fig. 2,) and a locking-screw d⁹, the head of which is above the bed-plate, is adapted to be screwed into this extension and serves, in connection with the washer d¹⁰, as means for locking the sliding block to the bed-plate at any desired position in the length of the slot. By unscrewing the screw and loosening the washer the slide-block is adapted to be moved to any desired position to adjust the position of the fulcrum.

The front end of the slide or part C is adapted to be moved crosswise the bed on the pivot e, which attaches it to the end of the lever d³, by means of a cam-groove f in

the upper side of the cam-disk D', and a lever f', having a cam-pin to enter the cam-groove f. This lever is pivoted at f² to the under surface of the bed-plate and has a slot f³, which receives a pin f⁴ in the rear end of the lever f⁵. This lever f⁵ passes through a fulcrum-piece f⁶, which is mounted in the slide-block f⁷, and engages at f⁸ a cross-slide f⁹, forming a bearing-block for a pivotal connection f¹⁰, in which the slide or part C is adapted to be moved forward or back. The slide-block f⁹ is movable back and forth in a slot extending transversely the bed-plate. The block f⁷ has an upward extension f¹¹ into the longitudinal slot f¹² in the bed-plate, and it is fastened to the bed-plate, upon the upper side thereof, by a screw f¹³ and washer f¹⁴. (See Fig. 2.) By loosening the screw the slide-block may be adjusted to any desired position in the slot f¹², thereby moving the fulcrum of the lever f⁵, whereby the throw of the end of the lever is varied or adjusted, and the slide-block is then locked by the screw and washer in its adjusted position.

It will be seen that both devices for adjusting the longitudinal movement of the piece D and its cross movement are immediately and readily accessible to the operator and do not require that the machine be inverted or that parts be removed for the purpose of making these adjustments. It is necessary, of course, that the machine be provided with these adjustments in order to adapt it to sew buttons in which the distance between the eyes vary and also to sew on buttons having four eyes as well as two. It will be noticed that these devices not only act as adjusting devices whereby the extent of the movements of the part C, and consequently the button-holder, may be varied, but they also serve as means for rendering one or the other, or both, of the movements nugatory, as by moving either of the adjusting devices to the extreme end of its respective slot the movement which it controls may be entirely cut off from the part D and the button-holder without disconnecting it from the operating cam-grooves.

It will be seen that the lever d is so shaped that a portion of it extends under the cam-disk and a portion of it over the cam-disk, that the under portion is connected directly with the cam-groove operating it, and the upper portion has the extension to which the link d² is attached.

It will be seen that the lever f' is forked at its outer end, that one of the arms of the forks carries the cam-pin, and that the other arm has the slot f³, which receives the end of the pin f⁴, connecting it with the lever f⁵. It will also be seen that the extension d⁷ extends upward from one side of the slide-block d⁵ and that the said slide-block d⁵ acts not only to carry the pivotal connections d⁴, which are bearing-blocks having rounded surfaces dropped in a suitable holder and which permit also the sliding and adjusting movement

of the slide-block in relation to the lever d³, but that it also acts to partially support the lever and the link d², and I would also call attention to the fact that the slide-block or adjustable block f⁷ has a similar pivotal connection with the lever f⁵—that is, one which permits it to be adjusted lengthwise the lever.

Having thus fully described my invention, I claim and desire to secure by Letters Patent of the United States—

1. In a button-sewing machine, in combination, a flat bed having a slot d⁸, a movable button-holder located on said bed, means whereby said button-holder is moved to and fro lengthwise the bed and adjustable devices located beneath said bed, whereby the lengthwise movement of said button-holder may be adjusted or rendered nugatory, said devices comprising a slide carrying a movable fulcrum, a lever fulcrumed therein and connected both to said button-holder and to said means for moving said button-holder, a portion of said slide lying in said slot, and means for clamping it in place therein, as set forth. 90

2. In a flat-button-sewing machine, the combination of the flat bed having the long slot f¹², the stitch-forming devices, the button-holder, means for moving the button-holder to and fro crosswise the bed located beneath the bed, and devices for adjusting the extent of said movements of the button-holder or preventing them entirely, said devices comprising a slide, a movable fulcrum mounted thereon carrying a lever, means whereby one end of said lever is connected to said button-holder and the other end thereof to said work-plate, a portion of said slide extending into said slot, and a clamping device for moving said slide accessible from above the bed, as 105 and for the purposes described.

3. In a flat-button-sewing machine, the combination of the flat bed having the slots d⁸, f¹² extending through the same, the stitch-forming devices, the button-holder, means for moving the button-holder backward and forward lengthwise the bed and to and fro across the bed, devices for adjusting the extent of movements of said button-holder and rendering them or either of them nugatory, portions 115 of which carry rectangular slides which extend respectively through said slots in the bed and are adjustable therein to move the parts connected with them in a right line and are manipulated above the bed, as and for the 120 purposes described.

4. The combination in a button-sewing machine, of the stitch-forming devices, the button-holder, the slide or piece C, the cam-groove D, the lever d pivoted at d', one end of said lever being operated by said cam-groove D, the link d², the lever d³ connecting said link with the slide or piece C, the sliding block d⁵ carrying the movable fulcrum d⁶ for the lever d³, as and for the purposes described. 125

5. The combination in a button-sewing machine of the stitch-forming devices, the but-

ton-holder, the slide or piece C, the cam-groove f , the lever f' , the free end of which is connected to said cam, said lever being pivoted at f^2 and engaging at its free end also the lever f^5 , a moving fulcrum f^6 for said lever f^5 mounted in the slide-block f^7 , the cross-slide f^{10} and means for connecting it with said

slide-block f^7 , and means for adjusting said slide-block, all as and for the purposes set forth.
